UNITED STATES PATENT OFFICE

JOHN N. WHITEHOUSE, OF NEW YORK, N. Y.

FOUNTAIN PEN BARREL OR THE LIKE AND METHOD OF MAKING IT

Application filed February 15, 1929. Serial No. 340,311.

This invention relates to a new article of manufacture, in the form of a tube or barrel such as may constitute part of a fountain pen structure or the like; and the invention also relates to the method of making such article of manufacture.

It is known in the art to make fountain-pen barrels or the like of such materials as hard rubber, celluloid, and the like. A familiar practice in this connection is to take a solid bar of the material, drill it out to form a tube, and suitably shape the exterior. The material is initially made, by proper admixture of coloring matter, veining, striation, etc., so that it will present somewhat the appearance of marble, onyx, mother-of-pearl, etc. However, whatever visual effects there are in the finished article will be substantially limited to the surface of the article.

It is an object of my invention to produce in an economical manner and using pyroxylin sheet material, a fountain-pen barrel or the like which simulates very closely the appearance of mother-of-pearl, onyx, marble, etc., and which presents entirely different and more attractive visual effects than has been possible with any of the methods heretofore employed.

In the accompanying drawing, in which I have endeavored to show the material and the method employed in making the new article, and in which I have also shown a fountain pen, of which the new article forms a part:

Fig. 1 is a plan view showing a sheet of pyroxylin material, for instance celluloid, which is used in forming a fountain-pen barrel or the like;

Fig. 2 is a perspective view showing how the sheet illustrated in Fig. 1 is rolled in the forming of the tube or barrel, and

Fig. 3 is a perspective view illustrating a fountain pen whose barrel and cap have been made by my process.

Referring to the numerals on the drawing, there is shown in Fig. 1 a sheet of pyroxylin material which is in general characterized by the fact that it is translucent. This sheet also carries a design, and the design may include arrangements of one or more colors and/or variations in translucency as between

particular areas, or other markings, whether superficial or sub-surface or both. The sheet is rolled up, as indicated in Fig. 2, to form a tube. In this operation I may employ the technique suggested in my Patent No. 1,661,451, March 6, 1928, that is, roll the sheet on a mandrel submerged in a solvent bath. After the tube has been rolled to the desired wall thickness, it is allowed to dry on the mandrel and is thereafter turned and polished. No joint will be visible exteriorly, and the tube is now practically solid from the mechanical point of view. The result is that we have a tube in which there is a multiplicity of distinct layers of continuous translucent material carrying the design that was initially given to the sheet of material with which operations were started. In practice I find that about eight layers give good results, assuming a certain thickness of sheet say 10/1000ths. In the finished article the exterior layer of material exhibits all of the phenomena of reflection, refraction, diffusion, dispersion, and other changing visual effects due to interference of light reflected from the surface of the outer layer, modified and/or augmented by the visual effects due to the translucency characteristic of the outer layer, and affected by the translucency and design characteristics of the underlying layers, in their mutual effect upon each other and upon the outer layer. Thus assuming that the starting sheet was made to simulate the appearance of mother-of-pearl, it will be seen upon a comparison of Figs. 1 and 2 of the drawing, that the marking which I have indicated by the reference character 4 in Fig. 1, will appear also exteriorly of the tube whose rolling is indicated in Fig. 2. At the same time a marking which I have indicated by the reference character 5 in Fig. 1, and which in the rolling of the sheet is on a substratum of the finished tube, will be dimly visible from the exterior of the tube, as indicated in Fig. 2. I believe that while every interior layer more or less affects the general visual result, only the three outer layers can readily be identified in the finished article by inspection. The result is an article which has the superficial gleam of mother-of-pearl,

and in which from the remoter depths come the irridescence so characteristic of mother-of-pearl, with all the changes due to the general translucency of the material, the laminated structure, the indistinct emergence to vision of the design carried on the interior laminae, and the mutually modified reflection, refraction and diffusion that results when light plays upon the article. The end result is an approximation to mother-of-pearl which is unsurpassed in artificial substitutes, so far as I know. The salient feature of my new article seems to me to be the fact that whereas the design of the outer layer is clearly visible from the exterior, the design of underlying layers, while not clearly defined, nevertheless emerges to the vision, its very obscurity completing the illusion of mother-of-pearl. So far as I know I am the first to provide a fountain-pen barrel or the like made up of a multiplicity of distinct layers of continuous translucent pyroxylin sheet material carrying a design, so that light may penetrate through at least a plurality of the layers, with the resulting optical effects which I have indicated. In this respect my article differs from those which, as suggested above, are drilled out of solid material, because with the latter there is substantially no penetration of light through the wall of the tube, and consequently whatever optical effects there are must be limited to surface effects.

I claim:

- 35 1. As a new article of manufacture, a tube for fountain-pen barrels, caps, and the like, comprising a multiplicity of distinct layers of continuous translucent sheet material carrying a design, the designs of the respective 40 superimposed layers being combined to impart to the finished article the appearance of a blended design of appreciable depth.
2. As a new article of manufacture, a tube for fountain-pen barrels, caps, and the like, 45 comprising a multiplicity of distinct layers of continuous translucent sheet material carrying a design, such layers being united by surface merger, the designs of the respective superimposed layers being combined to impart to the finished article the appearance of a blended design of appreciable depth.

In testimony whereof I affix my signature.

JOHN N. WHITEHOUSE.
